[57] CLAIM

The ornamental design for a mower handle mount, as shown and described.

DESCRIPTION

FIG. 1 is a perspective view of a mower handle mount showing my new design;

FIG. 2 is a front elevational view thereof;

FIG. 3 is a side elevational view thereof;

FIG. 4 is a rear elevational view thereof;

FIG. 5 is a bottom plan view thereof; and,

FIG. 6 is a top plan view thereof.

The appearance of the side opposite that shown in FIG. 3 is a mirror image of FIG. 3.

Fig. 1
